CLAIM

The ornamental design for a front panel of an in-wall fan controller with indicator component, as shown and described.

DESCRIPTION

FIG. 1 is a perspective view of a front panel of an in-wall controller according to a first example embodiment of the design;

FIG. 2 is a front view of a front panel of an in-wall controller according to the first example embodiment of the design; FIG. 3 is front view of a front panel of an in-wall fan controller with a transitional indicator component showing a first indicator configuration in the transitional indicator component according to a second example embodiment of the design;

FIG. 4 is a front view of a second indicator configuration in the transitional indicator component of the second example embodiment of the design;

FIG. 5 is a front view of a third indicator configuration of the transitional indicator component of the second example embodiment of the design; and,

FIG. 6 is a front view of a fourth indicator configuration of the transition indicator component of the second example embodiment of the design.

The subject matter of example aspects of the present disclosure includes a process or period during which a transitional indicator presented on a front panel of an in-wall fan controller changes among a plurality of indicator configurations. The process or period in which one interface configuration transitions into another interface configuration forms no part of the claimed design, nor is the order of the figures restrictive of a particular sequence in which the interface configurations appear on the front panel of the in-wall fan controller.

(Continued)

The broken lines shown in the drawings are for the purpose of illustrating portions of the front panel of an in-wall fan controller with an indicator component that form no part of the claimed design.
